(57) **CLAIM**

The ornamental design for a hydraulic drive for high-voltage circuit breaker, as shown and described.

DESCRIPTION

The patent or application file contains at least one drawing executed in color. Copies of this patent with color drawing(s) will be provided by the Office upon request and payment of the necessary fee.

FIG. 1 is a perspective view of a hydraulic drive for high-voltage circuit breaker showing our new design.

FIG. 2 is a first side elevational view thereof.

FIG. 3 is a second side elevational view thereof.

FIG. 4 is a third side elevational view thereof.

FIG. 5 is a fourth side elevational view thereof.

FIG. 6 is a bottom plan view thereof; and,

FIG. 7 is a top plan view thereof.
